(57) **CLAIM**

The ornamental design for a urine specimen collector for use by females, as shown and described.

DESCRIPTION

FIG. 1 is a perspective view of a urine specimen collector for use by females;

FIG. 2 is a side view thereof (opposite side view is mirror image of this view);

FIG. 3 is a front view thereof (back is mirror image of this view);

FIG. 4 is a top view thereof; and,

FIG. 5 is a bottom view.

The broken line showing of parts of the drawings is included for the purpose of illustrating use and environment and forms no part of the claimed design.

1 Claim, 3 Drawing Sheets

FIG. 4

FIG. 5
